UNITED STATES PATENT OFFICE

JOHN R. REPLEGLO, OF DETROIT, MICHIGAN, ASSIGNOR TO KELVINATOR CORPORATION, OF DETROIT, MICHIGAN, A CORPORATION OF MICHIGAN

REFRIGERATED FOOD CABINET

Original application filed August 25, 1924, Serial No. 733,913. Divided and this application filed February 18, 1928. Serial No. 255,244.

This invention relates to machinery supports, and more particularly to supports for the condenser unit and associated mechanism of mechanical refrigerating apparatus, the present application being a division of my co-pending application Serial No. 733,913 filed August 25, 1924. Application Serial No. 733,913 has resulted in Patent No. 1,716,150 issued January 4, 1929.

10 An object of the invention is the provision of mechanical refrigeration apparatus having an improved mounting for the motor driven compressor designed to minimize noise incident to vibration thereof.

15 Another object of the invention is the provision of a resilient mounting for machinery which can be readily adjusted to permit accurate disposition of the machinery.

20 Other objects more or less incident to the foregoing will appear in the following description of the preferred embodiment of the invention as shown in the drawings.

In the drawings, Fig. 1 is a sectional view 25 of an ice cream cabinet with which my invention is shown associated;

Fig. 2 is a fragmentary sectional view of the cabinet, with the machinery support associated therewith, taken on line 2—2 of 30 Fig. 1;

Fig. 3 is another fragmentary sectional view taken on line 3—3 of Fig. 1;

Fig. 4 is a fragmentary sectional view of one of the rear spring supports for the 35 compressor;

Fig. 5 is a similar view of one of the front spring supports of the compressor;

Fig. 6 is a view similar to Fig. 4 but showing a shipping attachment applied;

40 Figs. 7 and 8 are views of the same character as Figs. 4 and 6 showing modifications.

Referring in detail to the constructions illustrated, the frame of the cabinet, which is preferably made to a considerable extent 45 of standard structural steel forms, is of the same general character as that illustrated in my pending application Serial No. 673,678 and includes longitudinally extending bottom members 1 and similar top members 2 and transverse bottom members 3. The

cabinet is divided by walls into a heat insulated refrigerated compartment 4 and a machinery containing compartment 5. An outer wall of the machinery compartment is closed by a removable plate 6 to provide 55 access to the machinery, and also to allow assembly with and removal of the machinery from the cabinet. Metal blocks 7 are preferably provided on the under side of the cabinet frame to suitably support it. 60

Suitable refrigerating machinery is arranged within the machinery compartment for refrigerating the heat insulated compartment 4. Such machinery includes a compressor having a crank case portion 8 and an upper portion surrounded by a condenser 9. A gear casing 10 is bolted with the compressor crank case and forms an integral structure therewith, the two casings forming a rigid frame structure. The 65 mechanism described will be referred to as the condensing unit, and for a further reference to the refrigerating apparatus reference may be had to my co-pending application herein referred to. 70

To render the operation of the refrigerating mechanism as quiet as possible, I have devised an improved resilient mounting for the condenser unit. Two brackets or lugs are formed on the rear sides of the casings 80 8 and 10 and to them are secured depending stud bolts 11. On these studs is arranged an apertured bar 12 with coiled springs 13 surrounding the studs between the bar 12 and the casing lugs and with springs 14 surrounding the lugs between the lower sides of the bar 12 and the heads of the bolts. The studs are fitted at their upper and lower ends with thimbles 15 and 16 which serve 85 to center the springs in relation to the studs and the apertures through the bar 12 are counterbored to receive and center the adjacent ends of the springs. The apertures in the bar 12 are large enough to provide a clearance between it and the studs. Bolts 90 serve to rigidly connect the bar 12 to the floor 18 of the cabinet. 95

At the front side of the condenser unit two upright studs 19 and 20 are rigidly secured to the floor 18 of the cabinet, and 100

on these studs is arranged an apertured horizontal bar 21 with springs 22 surrounding the studs and interposed between the bar 21 and centering thimbles 23 which are adjustably supported by nuts 24 on the studs. Similarly springs 25 are interposed between the upper sides of the bar 21 and centering thimbles 26 which engage abutment nuts 27 on the studs. The apertures 10 through the bar 21 afford clearance around the studs 19 and 20 and are counterbored (Fig. 5) to receive and center the adjacent ends of springs 22 and 25. The front side of the gear casing 10 is formed with a bracket or lug 28 which rests upon and is rigidly bolted to the bar 21.

With the construction described, the springs of the suspension devices yieldingly support the condenser unit and yieldingly hold it against movement in all directions. That is to say, by the simple expedient of centering the coiled springs relative to the studs and providing clearance between the studs and the apertured bars through which they pass, the plain and relatively inexpensive coil springs are enabled to afford a yielding and resilient support for the unit adapted to permit limited movement of the unit and in any and all directions. In mounting the condenser unit in its compartment of the cabinet, the rear spring supports are preferably assembled on the unit while the front spring supports are assembled on the floor of the cabinet. Then when the unit is lifted into position in its compartment it is necessary only to apply the two bolts 17 to secure the rear suspension rigidly to the cabinet floor and to apply the single bolt which secures the floor bracket 28 of the unit to the bar 21. When the unit has thus been placed in position in the cabinet the abutment nuts 24 and 27 of the floor spring suspension can be adjusted on their studs to level the unit and insure suitable clearance between it and the side walls of the compartment.

To permit the limited freedom of movement which the unit with such a spring suspension must have, the refrigerant conduits 29, 30 and 31 are made sufficiently long and are suitably disposed so that they will readily flex enough to accommodate the vibratory movements of the unit. The flexibility of the spring mounting, above described, is such that some means must be provided to secure the unit against undue movement and injury during shipment, and I provide the following simple means for that purpose. As shown in Figs. 4 and 6 the rear spring studs 11 have their lower ends tapped to receive the screws 32 which are extended upward through apertures in the underlying frame angle bar 33. By turning the screws 32 the ends of the studs 11 and drawn down 65 to firm engagement with the angle bar 33,

thus rigidly securing the condensing unit at its rear side. The front side of the unit is secured to the cabinet frame and casing structure by introducing a spacer sleeve 34 (Fig. 5) between the bar 21 and the floor 70 of the cabinet and inserting securing bolt 35, the bar 21 and the floor being apertured to receive said bolt. These securing devices are very readily applied and detached and serve when applied to safely hold the condenser unit against dangerous movement during shipment.

Fig. 7 indicates a slight modification of the rear securing device illustrated in Figs. 4 and 6. In this modification, by simply introducing a spacer 36 between the head of the stud 11 and the angle plate 33 the screw 32 serves to rigidly secure the stud to the plate without materially compressing the springs 13.

In Fig. 8 is shown another modification in which the lower end of a modified stud 37 is formed with a threaded extension 38 which projects through the aperture of the angle plate 33 and is adapted to be engaged by a nut 39 to draw the stud down until its head engages with the plate 33.

In the operation of the refrigerating mechanism extreme quietness is secured by the spring suspension of the condensing unit 95 because the amount of vibration transmitted from the unit to the cabinet walls is practically nil.

While I have shown and described the preferred constructions embodying my improvements it will be understood that the constructions illustrated can be more or less widely varied without departing from the invention, the scope of which is indicated by the appended claims.

What I claim is:

1. A resilient suspension device comprising, a supporting member and a frame member, a stud bolt having an intermediate portion loosely mounted in one of the members, a resilient element associated with each end of the stud bolt, means for retaining the resilient elements in operative relation between the member and the ends of the stud bolt, means for securing one end of the stud bolt rigidly to the other member, and means for securing the members rigidly together to render the suspension non-resilient.

2. A resilient suspension device comprising, a supporting member and a frame member, a stud bolt having an intermediate portion loosely mounted in one of the members, a resilient element associated with one end of the stud bolt, means for retaining the resilient element in operative relation between the member and the end of the stud bolt, means for securing the opposite end of the stud bolt rigidly to the other member, and means including a spacing sleeve for 130

securing the members rigidly together to render the suspension non-resilient.

3. A resilient suspension device comprising, a supporting member and a frame member, a stud bolt having an intermediate portion loosely mounted in one of the members, a resilient element associated with one end of the stud bolt, means for retaining the resilient element in operative relation between the member and the end of the stud bolt, means for securing the opposite end of the stud bolt rigidly to the other member, and means including a bolt and spacing sleeve for securing the members rigidly together to render the suspension device non-resilient.

In testimony whereof I hereunto affix my signature.

JOHN R. REPLOGLE.
